UNITED STATES PATENT OFFICE.

HARRY G. TALBOTT, OF BALTIMORE, MARYLAND.

WALL SEAT.

Application filed February 3, 1927. Serial No. 165,554.

My invention relates to wall furniture and has for its object to provide a seat adapted to support a single individual so arranged that when not in use it may be folded up and slid into a cavity in the wall and wholly concealed from view by a sliding panel. A particular object of the invention is to provide a seat of this character which will be simple in construction, easily operated to swing it from concealed position into operating position, and amply strong to sustain much more than the weight of any individual.

A further object of the invention is to provide a swinging seat so braced against depression from horizontal position that its outer end may be left without a supporting leg.

A further object of the invention is to provide a construction in which the seat and its bracing means may be swung bodily into the cavity in which it is to be received and wholly concealed by the sliding panel.

With the objects above indicated and other objects hereinafter explained in view my invention consists in the construction and combination of elements hereinafter described and claimed.

Referring to the drawings:

Figure 1 is a perspective view of my invention showing the seat in position for use.

Figure 2 is a central vertical sectional view of the construction shown in Figure 1.

Figure 3 is a view corresponding to Figure 2 but showing the device of my invention in closed position.

Figure 4 is a front view of the device, and

Figure 5 is a perspective view of the moving parts of the device and one of the uprights in which the parts are movable.

In the drawings 1 and 2 indicate vertical front boards and 3, 4 and 5 indicate cross boards connecting the vertical front boards 3 and 4. These boards and cross boards are preferably extended upward and laterally to form rectangular spaces for panels 5. 6 and 7 indicate side uprights extending rearward from opposite edges of front boards 1 and 2 at right angles thereto. The inner opposite faces of these side uprights 6 and 7 are alike in construction and description of one will be sufficient for both.

In the inner faces of these side uprights are found grooves 9 and 10, the upper groove 9 extending from a point near the upper end of the upright downward with a slight in-

clination to the rear somewhat more than half the distance to the lower end of the upright terminating a short distance below the level of the lower edge of cross board 4. 60 Groove 10 extends from a point about on a level with the upper edge of cross board 4 downward to the lower end of the upright at a slight inclination to the rear and is preferably parallel with groove 9. At its 65 front edge the upright is rabbeted to form a vertical guide way 11 extending from top to bottom of the upright. At the upper end of this guide way 11 a pulley 12 such as is commonly used in window construction is 70 set into the upright. At the rear of the upright near its upper end a similar pulley 13 is inset into the upright.

The guide ways 11 carry the edges of sliding panel 14. Chains 15 connected to the 75 edges of the sliding panel pass over pulleys 12 and are connected at their other ends with counter balance weights, (not shown).

17 indicates the seat of my device. At its rear end this seat is provided with trunnions 80 18 extending into the grooves 10 and arrangement being such that when the seat is swung upward it may be pushed downward so as to be back of the cross board 4. The length of the seat is such that when thus pushed down its upper, outer end will not be above the upper edge of cross board 4.

To the rear edge of the seat 17 slightly forward of the trunnions 18 is hinged at 19 the lower edge of a brace board 20 which is 90 provided near its upper end with trunnions 21 which are movable in grooves 9. To the rear end of the seat 17 are connected chains 22 which lead over pulleys 13 to counterweights 23.

At the upper ends of grooves 9 are inset into the uprights 6 and 7 metallic stop plates 24 and at the upper ends of grooves 10 are inset similar metallic stop plates 25 these stop plates serving to stop the trunnions 18 100 of the seat 17 and trunnions 21 of the brace board 20 respectively.

The seat 17 and the brace board 20 are preferably cut out slightly at these side edges as shown, for convenience in swinging them 105 into and out of position.

The seat 17 and the brace board 20 are each preferably formed of a single piece of strong material such as wood with the grain running vertically.

The front boards 1 and 2 and cross boards 3 and 4 with panels 5 are spaced away from

- the wall of the apartment in which they are to be used a distance corresponding to the width from front to rear of the uprights 6 and 7. When the seat is not to be used the 5 front end of the seat is swung upward on its trunnions carrying the lower end of the brace board to the rear so that as the seat is swung into contact with the brace board the two will slide downward easily against 10 the lifting force of the counterweights 23, into position in rear of the cross board 4 and the panel 5 below it. The sliding panel 14 may then be drawn up to close the opening through which the seat extended. 15 When the seat is to be used the sliding panel 14 is pushed down until its upper edge is at or below the upper edge of cross board 4 and the seat 17 and brace board are drawn upward and the seat swung outward and 20 downward. As the seat reaches its horizontal position its under face rests at a point near its rear end upon the upper edge of the cross board 4 while the upper face of its rear end bears upward against the lower end 25 of the brace board. The contact of the trunnions 18 of the seat with the stop plates 25 tends to hold the seat in horizontal position and the contact of the trunnions 21 of the brace board hold the brace board from 30 further upward movement so that the contact of the lower end of the brace board with the rear end of the seat holds it firmly against being swung downward out of horizontal position. 35 Having thus described my invention what I claim is:—
1. In wall furniture the combination of a pair of oppositely arranged uprights provided with two sets of ways in their inner faces, a cross bar connecting the front edges of the uprights at a height suitable to support a seat, the cross bar being so arranged 40 as to have a substantial space behind it, a seat provided near its rear end with trunnions extending into the forward set of ways of the uprights, adapted to be moved into and out of the space behind the cross bar, and to be swung on its trunnions into horizontal position, a brace board hinged to the 45 seat near its trunnions, said brace board be-

ing provided with trunnions near its free end extending into the rear set of ways, and means for limiting the upward movement of said brace board.

2. In wall furniture the combination of a pair of oppositely arranged uprights provided with two sets of ways in their inner faces, a cross bar connecting the front edges of the uprights at a height suitable to support a seat, the cross bar being so arranged 55 as to have a substantial space behind it, a seat provided near its rear end with trunnions extending into the forward set of ways of the uprights, adapted to be moved into and out of the space behind the cross bar, and to be swung outward on its trunnions into horizontal position, a brace board hinged to the seat near its trunnions, said brace board being provided with trunnions 60 near its free end extending into the rear set of ways, stops at the upper ends of said second set of ways adapted to limit the upward movement of said brace board and a sliding panel for closing the space above the cross bar.

3. In wall furniture the combination of a pair of oppositely arranged uprights provided with two sets of ways in their inner faces so inclined that their upper ends are nearer and their lower ends are further from the front edges of the uprights, a cross bar connecting the front edges of the uprights at a height suitable to support a seat, the cross bar being so arranged as to have a substantial space behind it, a seat provided 70 near its rear end with trunnions extending into the forward set of ways of the uprights, adapted to be moved into and out of the space behind the cross bar a brace board hinged to the seat near its trunnions, said 75 brace board being provided with trunnions near its free end and extending into the rear set of ways, and stops at the upper ends of said second set of ways adapted to limit the upward movement of said brace board.

In testimony whereof, I hereunto affix my signature.

HARRY G. TALBOTT.
